(57) **CLAIM**

The ornamental design for a boss for a scraper of a conveyor belt cleaning apparatus, as shown and described.

DESCRIPTION

FIG. 1 is a bottom right perspective view of a boss for a scraper of a conveyor belt cleaning apparatus illustrating the design of the present invention;

FIG. 2 is a bottom left perspective view of the boss for a scraper of a conveyor belt cleaning apparatus of FIG. 1;

FIG. 3 is a bottom view of the boss for a scraper of a conveyor belt cleaning apparatus of FIG. 1;

FIG. 4 is a top view of the boss for a scraper of a conveyor belt cleaning apparatus of FIG. 1;

FIG. 5 is a front view of the boss for a scraper of a conveyor belt cleaning apparatus of FIG. 1;

FIG. 6 is a right side view of the boss for a scraper of a conveyor belt cleaning apparatus of FIG. 1;

FIG. 7 is a left side view of the boss for a scraper of a conveyor belt cleaning apparatus of FIG. 1;

FIG. 8 is a top right perspective view of the boss for a scraper of a conveyor belt cleaning apparatus of FIG. 1; and, FIG. 9 is a top left perspective view of the boss for a scraper of a conveyor belt cleaning apparatus of FIG. 1.

In the figures, shading represents contour and not any particular color.

1 Claim, 4 Drawing Sheets
